UNITED STATES PATENT OFFICE

WILLIAM J. DURING, OF SYRACUSE, NEW YORK, AND NATHAN LESTER, OF CLEVELAND, OHIO, ASSIGNORS TO PRECISION CASTINGS COMPANY, INC., OF SYRACUSE, NEW YORK, A CORPORATION OF NEW YORK

DIE-CASTING MACHINE

Application filed September 23, 1929. Serial No. 394,675.

This invention relates to certain new and useful improvements in die casting machines and more particularly to the construction and operation of the ladle or delivery pot used in conveying the molten metal from a suitable melting pot to the inlet port of a die or mold and to the manner in which the metal is then ejected by compressed fluid, as air, into said die or mold.

The main objects of this invention is to provide a die casting machine which combines reliability and safety of operation with durability and simplicity of construction.

To this end, the ladle or delivery pot is pivotally mounted on a crosshead which is slidably mounted upon suitable guide rods positioned one at either side of the delivery pot and carried by the frame of the machine. The delivery pot is positively moved to and from the casting relation with the die by the reciprocal movement of the crosshead, which, in turn, is actuated by a rock arm which is connected by a link to the rear portion of the delivery pot, and at the same time, the ladle or delivery pot is rocked about its pivotal connection with the crosshead by an adjustable arm which is pivotally connected with said delivery pot and a stationary portion of the machine, as for instance, the stationary die supporting plate.

The compressed fluid for ejecting the molten metal can be admitted to the pressure chamber of the delivery pot only when said pot is in the casting position due to the fact that the fluid inlet duct provided for the pressure chamber in the delivery pot is only connected with the fluid inlet passage provided in the stationary die plate when the ladle or delivery pot is in casting relation with the die or mold. In other words, the pressure chamber in the delivery pot is disconnected from the compressed fluid conduit at all times except when the delivery pot is in casting position, therefore insuring a maximum degree of safety in the operation of the fluid.

Other objects and advantages relate to the detail of the structure and relation of the parts all as will more fully appear from the following description taken in connection

with the accompanying drawings, in which:—

Figure 1 is a top plan of a portion of a die casting machine comprising the different elements of this invention.

Figure 2 is a side elevation of the device as illustrated in Figure 1.

Figure 3 is a longitudinal vertical sectional view taken on line 3—3, Figure 1.

Figure 4 is a detailed transverse sectional view of the crosshead taken in the plane of the line 4—4, Figure 2.

As illustrated in the drawings, the device consists of a suitable frame or fire box —1— having a furnace chamber —2— therein and a suitable cover plate —3— secured to the upper end of the frame —1—. A suitable melting pot —4— for containing molten metal is supported by the cover plate —3— in said furnace chamber —2—. A suitable stationary die supporting plate —5— is secured in any suitable manner to the frame of the machine in co-operative relation with the furnace and melting pot and has secured therein a receiving nozzle —6— adapted to register with the inlet port of the sprue die section of a die or mold not shown which is carried by the plate —5—. The ladle or delivery pot —7— as shown in the drawings, is of the goose-neck type and consists of a major vertically disposed portion —8— having a longitudinally disposed pressure chamber —9— therein and provided with a spout —10— which extends upwardly and forwardly from the lower portion of the delivery pot and is provided with a delivery nozzle —11— secured to the outer end thereof adapted when the delivery pot is in the casting position to register with the receiving nozzle —6— secured in the stationary plate —5—.

The delivery nozzle —11— is connected with the pressure chamber —9— by a duct —12— provided in the spout —10— so that when the delivery pot is in the charging position with the nozzle —11— submerged in the molten metal contained in the melting pot —4— as illustrated by dotted lines in Figure 3, the metal may gravitate through the nozzle —11— and duct —12— to

the pressure chamber —9— and when the delivery pot —7— is in the casting position, the metal may be forced from said chamber through the delivery nozzle —11— into the die or mold. A supporting bracket —13— for the delivery pot is secured by bolts or screws —14— to the upper end of the major portion —8— of said pot and has an arm —15— extending rearwardly therefrom which is provided with an aperture in the outer end thereof adapted to receive a horizontally disposed shaft —16— therethrough. The shaft —16— extends transversely of the machine in a plane above the melting pot —4— and is rotatably mounted at its ends in suitable brackets or blocks —17— which are, in turn, slidably mounted for longitudinal movement upon parallel horizontally disposed guide rods —18—.

The shaft —16— and block —17— combined to form a crosshead —28— for pivotally supporting the delivery pot —7— to swing about the axis of the shaft —16— and for longitudinal reciprocative movement in a rectilinear manner upon the guide rods —18—. The guide rods —18— are provided at one end with a reduced threaded portion —19— which is screw threaded into respective brackets —20—, said brackets being adjustably secured to the top surface of the cover plate —3— by screws or bolts —21— which pass through respective elongated holes —22— provided in the brackets —20— and screw threaded in the cover plate —3—. The other ends —19'— of the rods —18— are reduced in diameter and passed through suitable holes provided in upwardly extending lug —23— made integral with or secured to the forward end of the cover plate —3—. In this instance, the stationary die supporting plate —5— is provided with a pair of outwardly extending lugs —24— positioned one on each vertical side thereof in the plane of the respective lugs —23— formed on the cover plate —3—. The lugs —24— are also provided with holes similar to the holes in the lugs —23— and in co-operative alignment therewith for also receiving the forward end of the respective guide rod —18— therethrough so that when the rods are secured in the respective lugs —23— and —24—, the cover plate —3— and the stationary die supporting plate —5— will thereby be secured together. Each of the rods —18— are adjustably secured in the respective lugs —23— and —24— by a pair of nuts —25— and —26— screw threaded on the forward reduced end of the rod and positioned one on either side of the lugs.

In the upper portion of the brackets —20— is journaled a suitable rock shaft —27— disposed in a horizontal plane above and transverse of the frame —1— so that any adjustment of the rods —18— and brackets —20— longitudinally of the frame, will be transmit-

ted through the rock shaft —27— to the crosshead —28— and delivery pot —7— carried thereby to bring the delivery nozzle —11— of said pot into proper casting relation with the receiving nozzle —6—, the rock shaft —27— being operably connected with the delivery pot —7— by means of a rock arm —30— secured to said shaft to rock therewith and positioned intermediate the brackets —20—. The outer end of the rock arm —30— is slotted to receive one end of a link bar —31— which is pivotally connected therewith by a pin —32— while the other end of the link —31— is positioned in a suitable slot provided in a rearwardly extending lug —33— of the bracket —13— and pivotally connected therewith by a pin —34— arranged in a horizontal plane at the rear of the crosshead shaft —16— so that when the delivery pot is in the casting position as illustrated by full lines in Figure 3, the axes of the crosshead shaft —16— and the rock shaft —27— and the two pivotal pins —32— and —34— will be in the same straight line in a plane above the delivery nozzle —11— and intermediate said metal delivery nozzle and the fluid inlet nozzle for ejecting the metal from the chamber —9— which will be more fully hereinafter explained. In other words, the supporting shaft —16—, rock arm —30— and the connecting link —31— will be on the dead center when the delivery pot is in the casting position and will be prevented from passing downwardly beyond the dead center by an upwardly extending lug or stop —35— formed on the upper side of the cover plate —3— with the upper end thereof in contact with the undersurface of the rock arm —30— when said arm is in its lowered position.

The delivery pot support bracket —13— is also provided with an upwardly and forwardly extending arm —36— which is provided with a fluid-receiving nozzle —37— in the outer end thereof adapted when the delivery pot —7— is in the casting position to register with a fluid delivery nozzle —38— which is secured to the rear face of the upper portion of the stationary die supporting plate —5—. The fluid-receiving nozzle —37— is connected with the pressure chamber —9— of the delivery pot —7— by a suitable duct —39— provided in the arm —36—.

The fluid delivery nozzle —38— is in communication with a duct or fluid passage —40— provided in the upper portion of the die supporting plate —5—. The duct —40—, in this instance, extends downwardly from the inner end of the delivery nozzle —38— to a plane intermediate said fluid delivery nozzle and the metal receiving nozzle —6— and then extends outwardly in a horizontal plane to one of the vertical sides of the plate —5— where it is connected to any suitable source of fluid supply as a pressure pot not shown, by a pipe or conduit —41— which is screw

threaded in the adjacent portion of the die plate —5— in registration with the duct —40—. The delivery pot —7— is guided to swing vertically about the axis of the cross-head shaft —16— during the reciprocating movement of said crosshead to bring the nozzle —11— from the charging position submerged in the metal contained in the melting pot —4— into co-operative alignment with the receiving nozzle —6— by means of an adjustable supporting link —43— which has one end thereof pivotally mounted on a pin —44— which passes through one end of the link —43— and is secured in suitable upwardly extending spaced arms —45— provided on the upper horizontal edge of the die supporting plate —5—. The other end of the link —43— is pivotally mounted on a pin —46— which, in turn, is secured in the upper end of a bifurcated rod —47— which, in turn, is screw threaded in the upper portion of the bracket —13— in vertical alignment with the pressure chamber —9— of the delivery pot —7—.

The link —43— in this instance, is composed of a pair of brackets —48— and —49— which are pivotally mounted on the pins —44— and —46— respectively and provided in their adjacent outer ends with suitable internal threads for receiving the opposite end of a connecting rod —50— which is provided at its outer end with reverse threads so that by the proper manipulation of the connecting rod —50—, the pressure pot —7— and supporting bracket —13— may be adjusted to bring the delivery nozzle —11— and fluid-receiving nozzle —37— into simultaneous registration with a respective nozzle —6— and —38— when the delivery pot is in the casting position. The rod —50— may be secured in the adjusted position by suitable lock nuts —51— screw threaded thereon.

The bracket —13— in this instance, is adjustably secured to the horizontal shaft —16— by a screw —52— which may be locked in the operative position by a lock nut —53—. The shaft —27— may be rotated by any suitable means as by a force applied by hand or otherwise to the lower end of the arm —54— which is secured to the outer end of the shaft —27—.

The operation of the machine is as follows:—The ladle or delivery pot —7— is normally in the charging position with the nozzle —11— submerged in the molten metal contained in the melting pot —4— as illustrated by dotted lines in Figure 3 and with the crosshead —28— in the extreme rear portion, at which time the fluid-receiving nozzle —37— is disconnected from the fluid delivery nozzle —38—. Now when it is desired to do so, the delivery pot —7— may be raised to the discharging or casting position by rotating the shaft —27— to bring the rock arm —30— forward to the down position at rest upon the stop —35—. This will cause the

delivery pot to be carried forward by the crosshead —28— as said crosshead moves along the guide rods —18—. This forward movement of the delivery pot will also cause the link —43— to rock said delivery pot about the axis of the crosshead shaft —16— due to the lever action of said link upon the upper portion of the bracket —13— as the link —43— rocks about the axis of the pin —44—.

This rocking movement of the pot —7— is for the purpose of bringing the metal delivery nozzle —11— and the fluid-receiving nozzle —37— into the horizontal plane of the metal-receiving nozzle —6— and the fluid delivery nozzle —38— respectively at substantially the same time said delivery pot actuating toggle joint reaches the dead center position. That is, the link —43— acts to bring the nozzles —11— and —37— carried by the delivery pot —7— into co-operative alignment with the respective nozzles —6— and —38— secured to the stationary die-supporting plate —5— as the pot —7— and bracket —13— are moved forwardly through the straightening out of the construction formed by the rock arm —30— and link —31— which forces the nozzles —11— and —37— directly into the seat of the respective nozzles —6— and —38— supported by the plate —5—. It will be noted that the pressure with which the nozzles —11— and —37— are forced against the respective nozzles —6— and —38—, is regulated by adjusting the guide rods —18— in the respective lugs —23— and —24— and that said nozzles may be brought into horizontal alignment with the respective co-operating nozzles carried by the plate —5— by adjusting the bracket —13— on the shaft —16—.

After the delivery pot —7— has reached the casting position, the fluid, as air, under pressure, may be admitted by manipulating a suitable controlled valve into the duct —40— and through the nozzles —38— and —37— and duct —39— to the chamber —9— for ejecting the molten metal therefrom through the nozzles —11— and —6— into the die or mold after which the fluid may be again shut off from the duct —40— by reversing the movement of the controlled valve and then the pot —7— returned to the normal charging position within the melting pot —4— by reversing the movement of the lever —54— to rock the shaft —27— thereby returning the rock arm —30— to normal up position.

Although we have shown and described specific structures as constituting embodiments of this invention, we do not desire to restrict ourselves to the details of the structure or the relation thereof as various changes and modifications may be made within the scope of the appended claims.

We claim:

1. In a die-casting machine in combina- 130

tion, a delivery pot, a pivotal support for said delivery pot mounted for rectilinear movement towards and from a casting position, actuating means connected with said support, and additional means connected 5 with the delivery pot for producing a rocking movement of said pot during the rectilinear movement of the pivotal support.

2. In a die-casting machine in combination with a melting pot for containing molten metal and a die-supporting plate having a receiving nozzle therein, of a pressure chamber having a delivery nozzle connected therewith normally submerged in the molten metal, a reciprocating supporting means for 10 the chamber mounted for rectilinear movement toward and from said die-supporting plate, actuating means pivotally connected with the supporting means for moving said supporting means and chamber, and additional supporting means for moving the nozzle from the submerged position into operative alignment with the receiving nozzle and return during the movement of the first-mentioned supporting means.

25 3. In a die-casting machine in combination with a melting pot for containing molten metal and a die-supporting plate having a receiving nozzle therein, of a pressure chamber having a delivery nozzle connected therewith normally submerged in the molten metal, a reciprocating supporting means for the chamber mounted for rectilinear movement towards and from said die-supporting plate, actuating means pivotally connected with the supporting means for moving said supporting means and chamber, additional supporting means pivotally connected with the pressure chamber and with the die-supporting means for moving the nozzle from the submerged position into operative alignment with the receiving nozzle and return during the movement of the first-mentioned supporting means.

40 45 4. In a die casting machine in combination with a melting pot for containing molten metal and a die supporting plate having a receiving nozzle therein, of a delivery pot having a pressure chamber therein provided 50 with a delivery nozzle normally submerged in the molten metal, a reciprocating supporting means pivotally secured to the rear portion of said delivery pot to move said pot to and from the die plate and additional 55 supporting means mounted to rock about a fixed axis and pivotally secured to the upper portion of said delivery pot to cause the delivery nozzle to swing from the submerged position into operative alignment with the receiving nozzle and return during the reciprocating movement of the first-mentioned supporting means.

60 65 5. In a die casting machine in combination with a melting pot for containing molten metal and a die supporting plate having a

receiving nozzle therein of a delivery pot having a pressure chamber therein provided with a metal delivery nozzle and a fluid receiving nozzle connected therewith, said delivery nozzle being normally submerged in the molten metal, a reciprocating supporting means pivotally secured to the rear portion of the delivery pot to move said delivery pot to and from casting relation with the die-supporting plate, additional supporting 70 means mounted to rock about a fixed axis and pivotally secured to the upper portion of said delivery pot to cause the delivery nozzle to swing from the submerged position into operative alignment with the receiving nozzle and return during the reciprocating movement of the first-mentioned supporting means and means comprising a fluid conduit adapted to register with the fluid-receiving nozzle when the delivery pot is in the casting position for ejecting the molten metal from the pressure chamber through the delivery nozzle.

6. In a die casting machine in combination with a melting pot for containing molten metal and a die supporting plate having a receiving nozzle therein of a delivery pot having a pressure chamber therein provided with a metal delivery nozzle and a fluid receiving nozzle connected therewith, said delivery nozzle being normally submerged in the molten metal, a reciprocating supporting means adapted to move in a rectilinear manner pivotally secured to the rear portion of the delivery pot, additional supporting means 90 mounted to rock about a fixed axis and pivotally secured to the upper portion of said delivery pot to cause the delivery nozzle to swing from the submerged position into operative alignment with the receiving nozzle and return during the reciprocating movement of the first-mentioned supporting means and operating means for the delivery pot positioned in a plane intermediate said nozzles comprising a rock shaft connected by a toggle to the rear portion of the delivery pot for moving said delivery pot and delivery nozzle into casting relation with the receiving nozzle.

7. In a die casting machine in combination with a melting pot for containing molten metal and a die supporting plate having a receiving nozzle therein of a delivery pot having a pressure chamber therein provided with a metal delivery nozzle and a fluid receiving nozzle connected therewith, said delivery nozzle being normally submerged in the molten metal, a reciprocating supporting means adapted to move in a rectilinear manner pivotally secured to the rear portion of the delivery pot, additional supporting means 100 mounted to rock about a fixed axis and pivotally secured to the upper portion of said delivery pot to cause the delivery nozzle to swing from the submerged position into operative alignment with the receiving nozzle and return during the reciprocating movement of the first-mentioned supporting means and operating means for the delivery pot positioned in a plane intermediate said nozzles comprising a rock shaft connected by a toggle to the rear portion of the delivery pot for moving said delivery pot and delivery nozzle into casting relation with the receiving nozzle.

110 115 120 125 130

and return during the reciprocating movement of the first-mentioned supporting means and operating means for the delivery pot positioned in a plane intermediate said nozzles comprising a rock shaft connected by a toggle 5 to the rear portion of the delivery pot for moving said delivery pot and delivery nozzle into casting relation with the receiving nozzle and means for adjusting the rock shaft relatively to the die supporting plate to determine 10 the pressure at which the delivery nozzle engages the receiving nozzle.

8. In a die casting machine in combination with a melting pot for containing molten metal and a die supporting plate having a receiving nozzle therein of a delivery pot having a pressure chamber therein provided with a metal delivery nozzle and a fluid receiving nozzle connected therewith, said delivery nozzle 20 being normally submerged in the molten metal, a reciprocating supporting means adapted to move in a rectilinear manner pivotally secured to the rear portion of the delivery pot, additional supporting means mounted to rock about a fixed axis pivotally secured to the upper portion of said delivery pot to cause the delivery nozzle to swing from the submerged position into operative alignment with the receiving nozzle and return 30 during the reciprocating movement of the first-mentioned supporting means and operating means for the delivery pot positioned in a plane intermediate said nozzles comprising a rock shaft connected by a toggle to the rear portion of the delivery pot for moving said delivery pot and delivery nozzle into casting relation with the receiving nozzle, and fluid supply means comprising a fluid conduit adapted to register with the fluid-receiving 40 nozzle when the delivery pot is in the casting position for ejecting the molten metal from the pressure chamber through the delivery nozzle.

9. In a die casting machine in combination with a melting pot adapted to contain molten metal of a stationary die supporting plate having a metal receiving nozzle and a fluid conduit therein, of a delivery pot having a pressure chamber therein provided with a metal delivery nozzle and a fluid-receiving nozzle, said delivery nozzle normally submerged in the molten metal, a reciprocating supporting means adapted to move in a rectilinear manner pivotally secured to the rear portion of the delivery pot, additional supporting means mounted to rock about a fixed axis pivotally secured to the upper portion of the delivery pot to cause said pot to swing about the pivotal connection with the first-mentioned supporting means to bring the delivery nozzle from the submerged position into operative alignment with the metal-receiving nozzle and the fluid receiving nozzle into operative alignment with the fluid conduit and return during the reciprocating 50 movement of the first-mentioned supporting means, operating means for the delivery pot positioned in a plane intermediate said nozzles comprising a rock shaft connected by a toggle joint to the rear portion of the delivery pot for moving said delivery pot into casting relation with the die supporting plate, and means for adjusting the rock shaft relatively to the die-supporting plate to determine 60 the pressure at which the metal-receiving nozzle and the fluid conduit are engaged 65

movement of the first-mentioned supporting means.

10. In a die casting machine in combination with a melting pot adapted to contain molten metal of a stationary die-supporting plate 70 having a metal-receiving nozzle and a fluid conduit therein, of a delivery pot having a pressure chamber therein provided with a metal delivery nozzle and a fluid receiving nozzle, said delivery nozzle normally submerged in the molten metal, a reciprocating supporting means adapted to move in a rectilinear manner pivotally secured to the rear portion of the delivery pot, additional supporting means mounted to rock about a fixed 80 axis pivotally secured to the upper portion of the delivery pot to cause said pot to swing about the pivotal connection with the first-mentioned supporting means to bring the delivery nozzle from the submerged position 85 into operative alignment with the metal receiving nozzle and the fluid-receiving nozzle into operative alignment with the fluid conduit and return during the reciprocating movement of the first-mentioned supporting 90 means, and operating means for the delivery pot positioned in a plane intermediate said nozzles comprising a rock shaft connected by a toggle joint to the rear portion of the delivery pot for moving said delivery pot into 95 casting relation with the die-supporting plate.

11. In a die casting machine in combination with a melting pot adapted to contain molten metal of a stationary die-supporting plate 100 having a metal-receiving nozzle and a fluid conduit therein, of a delivery pot having a pressure chamber therein provided with a metal delivery nozzle and a fluid receiving nozzle, said delivery nozzle normally submerged in the molten metal, a reciprocating supporting means adapted to move in a rectilinear manner pivotally secured to the rear portion of the delivery pot additional supporting means mounted to rock about a fixed 105 axis pivotally secured to the upper portion of the delivery pot to cause said pot to swing about the pivotal connection with the first-mentioned supporting means to bring the delivery nozzle from the submerged position 110 into operative alignment with the metal-receiving nozzle and the fluid receiving nozzle into operative alignment with the fluid conduit and return during the reciprocating movement of the first-mentioned supporting 115 means, operating means for the delivery pot positioned in a plane intermediate said nozzles comprising a rock shaft connected by a toggle joint to the rear portion of the delivery pot for moving said delivery pot into 120 casting relation with the die supporting plate, and means for adjusting the rock shaft relatively to the die-supporting plate to determine the pressure at which the metal-receiving nozzle and the fluid conduit are engaged 125 130

by the metal delivery nozzle and fluid receiving nozzle respectively.

12. In a die-casting machine in combination, a delivery pot, a pivotal support for said pot mounted for rectilinear movement toward and from a casting position, actuating means pivotally connected with said support, and additional means pivotally connected with the delivery pot adapted to produce a rocking movement of the pot during the rectilinear movement of said pivotal support.

In witness whereof we have hereunto set our hands this 16th day of September, 1929.

WILLIAM J. DURING.
NATHAN LESTER.
